UNITED STATES PATENT OFFICE.

JOHN A. HOLMEN AND LILIAN O. HOLMEN, OF ST. PAUL, MINNESOTA.

CURTAIN-ROD.

1,204,570.

Specification of Letters Patent. Patented Nov. 14, 1916.

Application filed June 28, 1915. Serial No. 36,670.

To all whom it may concern:

Be it known that we, JOHN A. HOLMEN and LILIAN O. HOLMEN, citizens of the United States, residing at St. Paul, in the county of Ramsey and State of Minnesota, have invented a new and useful Improvement in Curtain-Rods, of which the following is a specification.

Our invention relates to improvements in curtain rods, and its primary object is to provide a curtain rod which is pivoted at one end and held by a spring catch at the other end, thus giving free access to the window by swinging the lace curtain to one side and giving chance for a better circulation when it is desired.

A further object of our invention is to provide detachable means for holding over draperies, curtains and the like, which will swing with the main curtain.

The simplicity of construction of our curtain rod or support makes it practical and easy to operate.

In the drawings forming part of this specification, Figure 1 is a view of a window showing our curtain rod attached thereto and one curtain swung back away from the window. Fig. 2 is a plan of one of the curtain rods detached from the window bracket. Fig. 3 is a front elevation of Fig. 2. Fig. 4 is a bottom view of Fig. 2. Fig. 5 is a plan of one of the brackets attached to the window casing. Fig. 6 is a side elevation of the bracket support. Fig. 7 is a perspective of the spring catch which holds the free end of the curtain rods. Fig. 8 is an alternate construction of the spring catch for holding the end of the curtain rods. Fig. 9 illustrates the curtain rod with the over drape bracket or supporting rod removed and an extension rod on the end of the same.

In the construction illustrated, A indicates a window casing upon which are secured vertical bearing brackets 2, at either side of the casing. The curtain rods 3 are formed of a rod or tube having one end bent down to form a vertical portion 4 which is journaled in the vertical bearing 2. A spring catch 5 is centrally secured to the window casing as illustrated in Fig. 1 to hold the free ends of the curtain rods 3 when the curtains are desired in front of the window.

When it is desired to use one curtain rod 3 which will extend across the whole window

an alternate spring catch 6 is used. The catch 6 is formed with a vertical pin 7 which fits into one of the bracket bearings 2 and is thus adapted to engage and hold the end of the rod 3 close to the window casing. A small hole 8 is provided in the free end of the rod 3 to allow the fastening by stitching with thread of the curtain to keep the same from coming off the rod 3 when it is disengaged from the catch 5 or 6.

An over drape supporting rod 9 is secured to a collar 10 which is adapted to slip over the rod 3. A notch 11 formed on the lower side of the collar 10 engages the vertical shank 4 of the rod 3 and holds the rod 9 against rotation and in a horizontal plane with the rod 3. The rod 9 is bent to curve from the collar 10 and lie parallel to the rod 3. A spring catch 12 is adapted to engage in the notch 13 formed on the top side of the rod 3 to hold the collar and rod 9 in position on the rod 3. The end of the spring can easily be engaged as the rod 3 is cut away at 14 to engage the spring 12 and thus release the collar 10 and rod 9 to remove the same. Tubular extensions 18 may be put on the rods 3 and 9 to lengthen or shorten the same. (Fig. 9.)

With the simple construction of this curtain rod the window can be opened and curtains turned back out of the way. The rods and bearing supports are small and are practically hidden from view by the curtains. It is obvious one or two main curtain rods can be used, and the over drape supports can be placed on one or two rods.

While we have illustrated one particular form of swinging curtain rod, we do not wish to confine ourselves to this particular construction but desire to have it understood that it can be carried out by other means within the scope of the following claims.

What we claim is:

1. A curtain support, comprising, a main horizontal rod, a bearing engaging one end of said rod allowing said rod to swing in a horizontal plane, spring means for detachably engaging the other end of said rod and means for supporting over drape curtains detachably carried by said main rod.

2. A curtain support, comprising, a main horizontal rod, a bearing engaging one end of said rod allowing said rod to swing in a horizontal plane, spring means for detach-

ably engaging the other end of said rod and a detachable rod for supporting over drape curtains carried by said main rod.

3. A curtain support, comprising, a main horizontal rod, a bearing engaging one end of said rod allowing said rod to swing in a horizontal plane, spring means for detachably engaging the other end of said rod and a detachable rod for supporting over drape curtains adapted to be slipped on said main rod having a spring catch to hold said detachable rod in place on said main rod.

4. A curtain support, comprising, a main horizontal rod, a journal bracket engaging one end of said rod allowing said rod to swing in a horizontal plane, a second journal bracket secured to the window casing and a spring catch mounted upon a shank, said shank being adapted to fit in said second journal and hold said spring catch in position to engage the free end of said main rod.

5. A curtain support, comprising, a main

horizontal rod, a journal bracket engaging one end of said rod allowing said rod to swing in a horizontal plane, means for supporting over drape curtains carried by said main rod and a notch in said supporting means for preventing the rotation of the same on said main rod.

6. A curtain support, comprising, a main horizontal rod journaled in a vertical bracket which allows said rod to swing in a horizontal plane, over drape supporting means carried on said main rod, means for preventing rotation of said over drape supporting means on said main rod and means for holding said over drape supporting means in longitudinal position on said main rod.
